UNITED STATES PATENT OFFICE.

GUSTAV SITTMANN, OF BROOKLYN, NEW YORK.

CHECK-PUNCH.

No. 924,112.

Specification of Letters Patent.

Patented June 8, 1909.

Application filed August 18, 1908. Serial No. 449,122.

To all whom it may concern:

Be it known that I, GUSTAV SITTMANN, a citizen of the United States, and resident of Brooklyn, in the county of Kings and State 5 of New York, have invented certain new and useful Improvements in Check-Punches, of which the following is a specification.

The object of my invention is to provide an improved check punch adapted to punch 10 holes in checks indicating the amount for which the check is drawn while at the same time impressing ink upon the check at each punched figure or symbol as a further protection against unauthorized alteration of 15 the check.

My invention also comprises the novel details of improvement and combinations of parts that will be more fully hereinafter set forth and then pointed out in the claims.

Reference is to be had to the accompanying drawings forming part hereof, wherein,

Figure 1 is a side view of a check protector embodying my invention; Fig. 2 is a central section thereof; Fig. 3 is a detail plan view; 25 Fig. 4 is a detail edge view looking from the right in Fig. 1; Fig. 5 is a detail perspective of the check-holding spring-plate; Fig. 6 is an inverted plan view of the device; Fig. 7 is a detail section taken above the check feeding 30 roll and die plate; Fig. 8 is a detail sectional view showing the punch-carrying disk and guide therefor; Fig. 9 is an enlarged central section of one of the punches and strippers; Fig. 10 is a detail section on the line 10, 10 in 35 Fig. 9, and Fig. 11 is a detail face view of the punch and strippers.

Similar characters of reference indicate corresponding parts in the several views.

A suitable frame is indicated at 1, and at 2 40 is a rotative disk or plate having a stem 2^a journaled in a bearing in frame 1 and provided at its upper end with a head or operating handle 3 for manually rotating the disk, said head bearing appropriate figures and 45 symbols A. Frame 1 is shown provided with a depending guide block 4 having a bore 4^a in which is located a spring 5 bearing against a sliding pin 6 projecting from said block and adapted to enter circularly dis- 50 posed seats 2^b in the upper surface of disk 2, which pin and seats serve to retain the disk in proper position for operation of the respective punches.

At 7 is a plunger guided in bore 4^a and 55 bearing upon spring 5.

At 8 is a handle pivotally connected with

frame 1, as at 8^a, shown supported by brackets 9 on said frame, which handle is shown forked at its inner end to straddle the stem 3^a and is suitably shaped at 8^b to bear 60 against the under surface of head 3 and also bent cam-like at 8^c to act upon plunger 7, the arrangement being such that when handle 8 is depressed plunger 7 will be pushed down to depress disk 2, the bent part 8^c of 65 the handle moving from under head 3 permitting the latter to descend, and when the handle is released spring 5, by pushing plunger 7 upwardly against the handle, will cause the part 8^c of the handle acting upon 70 head 3 to raise the latter and disk 2, whereby said disk is raised and lowered as required. Disk 2 carries a series of punching devices, 75 adapted in connection with a suitable die plate, to punch holes in checks when handle 8 is depressed. The punching devices are disposed annularly around disk 2 and as they are all substantially alike a description of one will suffice as follows:—Disk 2 is provided with a series of guides or sockets 10 open 80 from top to bottom through the disk and provided each with a vertically arranged slot 10^a, and in the guide 10 is a vertically sliding die-block 11 having a projection or web 11^a sliding in the slot 10^a to keep the 85 block from rotating. Said block at the upper end is provided with a threaded stem or screw 12 passing through a socket or counter bore 13 in which is located a spring 14 that bears against a cap or nut 15 threaded 90 on screw 12. At the opposite end block 11 carries punches 16 which extend downwardly and pass through holes in a printing plate or stripper 17 that is adapted to be impressed upon the check a for printing the outline of 95 the corresponding type, as indicated in Fig. 11. Punches 16 may be rigidly connected with block 11 by casting the latter upon the punches, it being understood that the punches for each figure or symbol will be 100 suitably arranged before block 11 is cast upon the punches. Stripper 17 is normally pressed outwardly substantially beyond or flush with the lower ends of punches 16, and for this purpose I have shown block 11 as 105 provided on opposite sides with vertical slots 11^b in which are located metal strips 18, the lower inwardly bent ends 18^a of which strips enter recesses 17^b in stripper 17 and the upper bent ends 18^b of said strips extend 110 over block 11 and spring 14 bears upon said ends 18^b, whereby said spring normally tends

to push stripper 17 outwardly, the normal position of the parts being shown in Fig. 9.

At 19 is a spring shown coiled around block 11 and bearing against the under side 5 of nut or cap 15 and also against guide 10, normally tending to press the punching devices upwardly, the flange of stripper 17 bearing against the under surface of disk 2 and thus limiting the upward movement of 10 the punching devices. The disk 2 is provided with radial slots 2^c that coincide with the corresponding slots 10^a, whereby the projection 11^a may slide freely downwardly, said slots 2^c being radially alined with the 15 corresponding seats 2^b, and receive guide finger 20 that is secured to frame 1 and projects inwardly, whereby as disk 2 is rotated to bring the desired punch in operating position the corresponding slot 2^c will be brought 20 in line with guide finger 20, so that when disk 2 is depressed said guide finger will retain the disk in proper position and guide the same as it descends. The guide finger 20 is shown as having two spring like fingers 25 20^a bent from a plate 20^b that is secured to frame 1, whereby said fingers may be bent as required to cause accurate alinement of the punches 16 as they descend. The punches are depressed by means of a finger 7^a that is 30 secured to plunger 7 and extends in line with an opening 1^b in frame 1 in position coinciding with guide finger 20, whereby when disk 2 is turned to bring one of the punching devices in operating position and then handle 35 8 is depressed, finger 7^a will bear upon cap 15 to push the corresponding punching devices downwardly.

At 21 is a die plate located in proper position with respect to the check punching 40 point and beneath disk 2, which die plate is provided with a suitable series of holes 21^a adapted to receive the punches 16. Said holes are located in suitable formation such that the outline of any figure or symbol to be 45 punched may be produced by such series of holes, that is to say, the punches for any figure or symbol are located in their respective block 11 in such relation that such punches will pass through the corresponding 50 holes 21^a in die plate 21. The die plate 21 is attached to a supporting plate 22 secured in a suitable recess or opening in frame 1; plate 22 having a suitable opening 22^a with which the holes 21^a in die plate 21 are alined (see 55 Fig. 7). The checks *a* are passed edgewise through the lateral opening or recess *B* in frame 1 and over plates 21, 22 (see Figs. 1 and 2), whereby when any of the punches are depressed the outline of the figure or 60 symbol will be punched in the check.

To feed the check forwardly for each figure or symbol punched therein, I provide a feeding roller 23 shown provided with flanges 23^a adapted to bear on the check and projecting 65 through the opening 22^a of plate 22, the shaft

24 of said roller being shown journaled in bearings 25 which may be formed by punching out the metal of plate 22, as shown in Fig. 2. Shaft 24 carries a ratchet 26 adapted to be engaged by a spring-pressed pawl 27 70 carried by an arm 28 depending from disk 2, which arm is shown connected with said disk by a screw 29 in such manner that said disk may revolve without revolving the arm, the arm being shown bent around the inner edge 75 22^c of plate 22 and by bearing on said plate is kept from rotating, yet said arm will rise and fall with disk 2, the upwardly extending part 28^a of arm 28 being permitted up and down motion relatively to edge 22^c, whereby 80 as disk 2 is depressed pawl 27 will slip over ratchet 26, and as disk 2 rises said pawl will rotate ratchet 26 and roller 23 a suitable distance to feed the check a step forward for 85 each figure or symbol punched therein. A 85 suitable back-stop spring 30 secured to plate 22 and bearing against ratchet 26 resists reverse rotation of said ratchet. The check is held firmly against flanges 23^a of roller 23 by means of a spring plate 31, the inner end of 90 which is shown secured to plate 22 by being bent around at 31^a and riveted to plate 22, and the outer part of plate 31 is provided with a finger piece 31^b for lifting the plate. Said plate is provided with an opening 31^c 95 alined with die plate 21 for the passage of punches 16, and said plate 31 has bearing rollers 32 alined with flanges 23^a to bear on the check to press the latter against said flanges, which rollers 32 are shown journaled 100 on studs 33 secured on plate 31 by ears 34 stamped out of such plate and bent around said studs.

At 35 is an inking pad, shown in the form of a roller journaled upon a stud 36 secured upon arm 28, and may comprise a circular felt pad, adapted for engagement with the lower ends of strippers 17 or the raised parts 17^a thereof for inking the same as disk 2 is rotated.

With a check punch constructed in accordance with my improvements, plate 31 will be lifted and the check slid edgewise over the plate 22 in proper position and plate 31 will then be released; thereupon head 3 will be rotated to bring the desired figure or symbol *A* of the punching devices in line with die plate 21, during which time the type forms will be engaged by the inking roller, the stud 6 resting in the appropriate seat 2^b, with the corresponding slot 2^c in line over guide finger 20, and then handle 8 will be depressed whereupon plunger 7, through spring 5, will push disk 2 downwardly, (pawl 27 slipping over the ratchet 26) and simultaneously the corresponding punching device will be pushed downwardly by finger 7^a engaging the cap 15 until the corresponding stripper 17 bears upon the check and imprints thereon the outline of the figure or symbol *A*, and 130

by a continued downward movement of handle 8 on cap 15 the block 11 and punches 16 will be pushed downwardly and through the stripper 17, through the check and into or 5 through the corresponding holes 21^a in die plate 21, and when the handle is released the springs 5 and 19 will raise the parts to their normal position, pawl 27 thereupon through ratchet 26 rotating roller 23 one step to feed 10 the check for the next punching operation.

While I have illustrated and described a practical embodiment of my invention it will be understood that changes may be made in details of construction shown and described 15 without departing from the spirit of my invention.

Having now described my invention what I claim is:—

1. A check punch comprising a rotative 20 disk, punches carried thereby and movable relatively thereto, a stripper movable with the punches and also relatively thereto, means for reciprocating the punches and stripper, the latter having a printing surface, 25 means to ink said surface, and a die plate to co-act with the punches and type form. 30 2. A check punch comprising a rotative disk, punches carried thereby and movable relatively thereto, a stripper movable with the punches and also relatively thereto, means for reciprocating the punches and stripper, the latter having a printing surface, 35 means to ink said surface, a die plate to co-act with the punches and stripper, and means for feeding a check step by step as punched.

3. A check punch comprising a rotative disk, punches carried thereby and movable relatively thereto, a stripper movable with the punches and also relatively thereto, 40 means for reciprocating the punches and stripper, the latter having a printing surface, means to ink said surface, a die plate to co-act with the punches and stripper, and means for raising and lowering the disks.

4. A check punch comprising a rotative disk, punches carried thereby and movable relatively thereto, a stripper movable with the punches and also relatively thereto, 45 means for reciprocating the punches and stripper, the latter having a printing surface, means to ink said surface, a die plate to co-act with the punches and type form, means for raising and lowering the disk, and means for feeding a check step by step as punched.

5. A check punch comprising a rotative disk, punches carried thereby and movable relatively thereto, a stripper movable with the punches and also relatively thereto, 50 means for reciprocating the punches and stripper, the latter having a printing surface, means to ink said surface, a die plate to co-act with the punches and type form, means for feeding a check step by step as punched, and means for guiding the disk as it reciprocates.

6. A check punch comprising a rotative

disk provided with guides, blocks adapted to reciprocate in said guides and provided with punches, strippers having holes receiving said punches, means for supporting said strippers to have movement relatively to the 70 punches, means for operating said punches independently of the strippers, the latter having a printing surface, means to ink said surface, and a die plate for alinement with the strippers and punches. 75

7. A check punch comprising a rotative disk provided with guides, blocks adapted to reciprocate in said guides and provided with punches, strippers having holes receiving said punches, means for supporting said 80 strippers to have movement relatively to the punches, means for operating said punches independently of the strippers, the latter having a printing surface, means to ink said surface, a die plate for alinement with the 85 strippers and punches, and means for feeding checks after they are punched.

8. A check punch comprising a rotative disk provided with guides, blocks adapted to reciprocate in said guides and provided with punches, strippers having holes receiving said punches, means for supporting said 90 strippers to have movement relatively to the punches, means for operating said punches independently of the strippers, the latter 95 having a printing surface, means to ink said surface, a die plate alined with the strippers and punches, and means for raising and lowering said disk.

9. A check punch comprising a rotative 100 disk provided with guides, blocks adapted to reciprocate in said guides and provided with punches, strippers having holes receiving said punches, means for supporting said 105 strippers to have movement relatively to the punches, means for operating said punches independently of the strippers, the latter having a printing surface, means to ink said surface, a die plate for alinement with the strippers and punches, a check-feeding roller, 110 connected therewith, a dog connected with said disk, and a plate having rollers to co-act with said feeding roller.

10. The combination of a rotative disk 115 provided with guides, blocks located in said guides, means to prevent rotation of said blocks and to permit them to slide in the guides, punches carried by said blocks, a finger to operate said punches, a handle adapted to depress the finger and to raise the disk, a spring operating with said finger and handle to raise them, a die plate for alinement with said punches, and means for feeding checks as they are punched. 120

11. The combination of a rotative disk 125 provided with guides, blocks located in said guides, means to prevent rotation of said blocks and to permit them to slide in the guides, punches carried by said blocks, a finger to operate said punches, a handle 130

- adapted to depress the finger and to raise the disk, a spring operating with said finger and handle to raise them, a stripper having holes receiving said punches, means to permit said 5 stripper to have movement independently along said punches, a die plate for alinement with said punches and stripper, and means for feeding checks.
12. The combination of a rotative disk, 10 guides carried thereby, blocks in said guides, punches carried by said blocks, strippers having holes receiving said punches, a spring to normally push the stripper outwardly, means to limit the outward movement of 15 said stripper, a spring to raise the stripper, block, and punches, a finger to operate the stripper and punches, a die block to co-act with said stripper and punches, and means for feeding checks.
13. The combination of a rotative disk, 20 guides carried thereby, blocks in said guides, punches carried by said blocks, strippers having holes receiving said punches, a spring to normally push the stripper outwardly, means to limit the outward movement of 25 said stripper, a spring to raise the stripper, block and punches, a finger to operate the stripper and punches, a die block to co-act with said stripper and punches, a roller having flanges, 30 means for operating said roller step by step for each operation of the punches, a spring plate having rollers to co-act with said flanges for feeding checks, and means to operate said roller step by step.
14. A check punch comprising a rotative disk, punches carried thereby and movable relatively thereto, a stripper movable with the punches and also relatively thereto and provided with a type printing surface, means 40 for reciprocating the punches and stripper, a die plate to co-act with the punches and stripper, and means for inking the stripper.
15. A check punch comprising a rotative disk, punches carried thereby and movable 45 relatively thereto, a stripper movable with the punches and also relatively thereto and provided with a type printing surface, means for reciprocating the punches and stripper, a die-plate to co-act with the punches and stripper, and a pad located in position to be engaged by the stripper as the latter revolves.
16. A check punch comprising a rotative

disk, punches carried thereby and movable relatively thereto, a stripper movable with 55 the punches and also relatively thereto and provided with a type printing surface, means for reciprocating the punches and stripper, a die plate to co-act with the punches and stripper, and an inking pad carried by the 60 disk in position to be engaged by the stripper as it revolves.

17. A check punch comprising a rotative disk, punches carried thereby and movable relatively thereto, a stripper movable with 65 the punches and also relatively thereto, means for reciprocating the punches and stripper, a die plate to co-act with the punches and stripper, a roller, a spring-plate having rollers to co-act with the first named 70 roller, a ratchet connected with said roller, an arm connected with said disk and carrying a pawl to engage said ratchet, and an inking pad carried by said arm adapted to engage said stripper.

18. A punching and printing device comprising a block provided with punches, a stripper having holes receiving said punches, and provided with a printing surface, means 80 slidably connecting said stripper with said punches, and a spring co-acting with said means and with said block for holding the stripper in normal position with relation to the punches.

19. A punching and printing device comprising a block, punches carried thereby, a stripper having holes receiving said punches, strips connected with said stripper and having projections co-acting with said block, and a spring co-acting with said strips and block.

20. A punching and printing device comprising a block, punches carried at one end thereof, a stripper having holes receiving said punches, a cap carried at the opposite end of the block, strips slidably connected with said block and also connected with said stripper, and a spring co-acting with said strips and said cap for holding the stripper in normal position with respect to the punches.

Signed at New York city, in the county of 100 New York, and State of New York, this 14th day of August, A. D. 1908.
